MAN'S SHORTS

William Murphey, Chattanooga, Tenn.

Application July 18, 1939, Serial No. 285,197

5 Claims. (Cl. 2—224)

The object of my invention is to provide certain improvements in men's undergarments, known as shorts.

It is also an object of my invention to provide a novel construction having a triple-ply section; to provide a novel construction, whereby a concealed fly is provided, and to provide a construction that is ornamental as well as useful and which will conform to the anatomy and contour of the body.

I attain these and other objects of my invention by the means illustrated in the accompanying drawings, in which—

Figure 1 is a front view of a pair of shorts embodying my invention with a portion turned up and shown in perspective;

Fig. 2 is a section on line 2—2 of Figure 1 with the portion of the garment thus sectioned, spread out;

Fig. 3 is a section on line 3—3 of Fig. 2 but extended the full length of the garment;

Fig. 4 is a rear view of the shorts with the waist in open position;

Fig. 5 is a front view of a modified form of the invention;

Fig. 6 is a fragmentary section through the front of the modified form of the invention shown in Fig. 5, inverted;

Fig. 7 is schematic diagram of the parts forming the garment of the form shown in Figs. 1 to 4 inclusive;

Fig. 8 is a diagrammatic view of the central strips including the plural rear central sections in the modification of the form shown in Fig. 7;

Fig. 9 is a diagrammatic view of the central strips including the single rear central section in the form of the invention shown in Fig. 5;

Fig. 10 is a diagrammatic view of one-half of the frontal element of Fig. 1; and—

Fig. 11 is a diagrammatic view of the entire element 37 forming half of each layer used in the frontal element of Fig. 5.

Like numerals designate like parts in each of the several views.

Referring to the accompanying drawings and especially to Fig. 7 which shows the elements diagrammatically, my garment has a trapezoidal rear central section 1 having a concave lower edge 2. The sides of this central section are parallel. Connected to section 1 is an inner crotch section 3 having a rear convex upper edge

4, like opposite arcuate side edges 5 and like front beveled or diagonally slanting edges 6. Also connected to edge 2 of member 1 is an outer crotch section 7 of identical shape to section 3

and having a convex rear edge 8, arcuate side edges 9 and beveled front edges 10. Trapezoidal rear side sections 11 are stitched along their rear edges 12 to the adjacent edges of the respective central sections. Sections 11 have relatively short side edges 13 and beveled edges 14 extending from the end of the lower short side edges 13 to the lower ends of the long side edges 12.

The trapezoid type of left front section 15 is stitched along its side edge 16 to the side edge 13 of the adjacent rear side section and is provided with an arcuate bottom edge 17 which is a part of the leg opening and has a beveled or diagonally slanting front edge 18 extending from edge 17 to the top of the substantially horizontal edge of the section.

The front of the garment is completed by a front section 19 having a side edge 20 of corresponding length to the side edge 13 of rear section 11 and stitched to that member. Section 19 also has an arcuate lower edge 21 forming part of the leg opening. It also has a preferably concavely curved transverse lower free edge 22 constituting the inner edge of the concealed fly. It also has a beveled or diagonally slanting edge 23 extending adjacent to and stitched to the beveled front edge 18 of the left front section 15, as shown most clearly in Figs. 2 and 4.

Lines of stitching 24 connect the adjacent edges of rear side sections 11 with the rear central section 1 and the corresponding edges of crotch strips 3 and 7. A preferably convex line of stitching 25 secures the lower end of rear central section 1 to the crotch sections 3 and 7.

I provide a novel front diagonal trimming strip 26 extending from the waist band 35 to the left leg band 34; this trimming strip being secured throughout its length to the garment by the double line of stitching 27 and concealing the respective beveled edges 18 and 23 of front strips 15 and 19 respectively.

I also provide a reversely disposed trimming strip 28 extending from the waist band 35 to the right leg band 34. Double lines of stitching 29 secure the upper portion of the trimming strip 28 to the front strip 15. The lower portion 30 of the trimming strip 28 is free from the adjacent front right section 19 of the garment, the lower portion of that section constituting a concealed fly.

Double lines of stitching 31 secure the lower portion of trimming strip 28 to the upper horizontal edges of the crotch strips 3 and 7 respectively. The line of stitching 32 fastens together

the beveled or diagonal edges 18 and 23 of members 15 and 19 respectively.

I provide novel leg bands 33 formed of the same knit material as the body of the garment and secured around the leg openings by the line of stitching 34. I also provide an elastic waist band 35 secured to the waist of the garment by stitching 36.

Referring to Fig. 8, I may provide a modification of the garment having a double rear central section 1a of the same shape and size as section 1.

Figs. 5, 9, and 11 illustrate the modification of the invention in which the crotch members 3 and 7 are replaced by pairs of crotch members 37 secured together by a central line of stitching 38 and which together form a central crotch element of greater width and consequently more fullness at this portion of the garment, as shown in Figs. 5 and 9.

The construction described and shown provides a garment of double thickness in the crotch section and of triple thickness in the lower front portion. As the garment is made from lightweight knit material with leg bands formed of the same material, it affords comfort to the wearer.

The front section 19 of the peculiar shape shown provides a concealed fly and terminates in the front edge 22, having opening 30 under the sections 3 and 7 (or in the modification shown in Figs. 5, 9, and 11, under the section 37).

The trimming strip 26 has a double function in concealing the lines of stitching 32, as well as reenforcing the garment and giving it a more ornamental appearance, while trimming strip 28 has the double function of concealing and reinforcing the edge portion of the adjacent edges 6 and 10 of crotch sections 3 and 7 (or of the substituted enlarged crotch section 37 in the modified form), and in giving the garment a balanced and ornamental appearance.

The garment as a whole is of very light weight while providing additional thickness at certain portions where desirable, is flexible throughout including the portions adjacent the leg openings, has no buttons to come off; and in the modification illustrated in Figs. 5 and 9 and 11, provides additional space to accommodate the genital organs.

What I claim is:

1. In a garment of the type described, the combination of a central rear section of substantially uniform width from end to end, like lateral rear sections each having a slanting bottom edge, a pair of like crotch sections having curved side edges and terminating in opposite diagonally disposed slanting front edges, the front section having its side edge of similar length to the side edge of the adjacent rear side section and having the bottom edge curved to the shape of the leg of the wearer and having a diagonally disposed front edge aligned with the adjacent diagonal edges of the crotch section, a mating front section having its side edge of the same length as the side edge of the corresponding rear side section and having its lower edge curved to conform to the shape of the leg of the wearer and having an opposite diagonally disposed edge aligned with the diagonal edge of the other front section and terminating in a transverse free edge portion which constitutes the lower edge of the concealed fly, and lines of stitching securing all of the aforesaid sections together.

2. In a garment of the type described, the com-

bination of a central rear section of substantially uniform width from end to end, like lateral rear sections each having a slanting bottom edge, a pair of like crotch sections having curved side edges and terminating in opposite diagonally disposed slanting front edges, the front section having its side edge of similar length to the side edge of the adjacent rear side section and having the bottom edge curved to the shape of the leg of the wearer and having a diagonally disposed front edge aligned with the adjacent diagonal edges of the crotch section, a mating front section having its side edge of the same length as the side edge of the corresponding rear side section and having its lower edge curved to conform to the shape of the leg of the wearer and having an opposite diagonally disposed edge aligned with the diagonal edge of the other front section and terminating in a transverse free edge portion which constitutes the lower edge of the concealed fly, lines of stitching securing all of the aforesaid sections together, a narrow strip of trimming reinforcing and covering and concealing the diagonally disposed edges of the front section and the aligned diagonal edges of the crotch sections and stitched to the garment to reinforce it, and a reversely disposed strip reinforcing and covering the opposite diagonal edges of the crotch sections but free from the front section therebeneath which underlaps said crotch sections to provide a concealed fly, the upper portion of said strip being stitched to the outer front section.

3. In a garment of the type described, the combination of a central rear section of substantially uniform width from end to end, like lateral rear sections each having a slanting bottom edge, a pair of like crotch sections having curved side edges and terminating in opposite diagonally disposed slanting front edges, the front section having its side edge of similar length to the side edge of the adjacent rear side section and having the bottom edge curved to the shape of the leg of the wearer and having a diagonally disposed front edge aligned with the adjacent diagonal edges of the crotch section, a mating front section having its side edge of the same length as the side edge of the corresponding rear side section and having its lower edge curved to conform to the shape of the leg of the wearer and having an opposite diagonally disposed edge aligned with the diagonal edge of the other front section and terminating in a transverse free edge portion which constitutes the lower edge of the concealed fly, lines of stitching securing all of the aforesaid sections together, a narrow strip of trimming covering and concealing the diagonally disposed edges of the front section and the aligned diagonal edges of the crotch sections and stitched to the garment to reinforce it, a reversely disposed strip covering the opposite diagonal edges of the crotch sections but free from the front section therebeneath which underlaps said crotch sections to provide a concealed fly, the upper portion of said strip being stitched to the outer front section, and leg bands of the same flexible material as the body of the garment folded over and concealing the edges forming the leg openings and stitched to the garment.

4. In a garment of the type described, the combination of a central rear section of substantially uniform width from end to end, like lateral rear sections each having a slanting bottom edge, a pair of like crotch sections having curved side

edges and terminating in opposite diagonally disposed slanting front edges, the front section having its side edge of similar length to the side edge of the adjacent rear side section and having the bottom edge curved to the shape of the leg of the wearer and having a diagonally disposed front edge aligned with the adjacent diagonal edges of the crotch section, a mating front section having its side edge of the same length as the side edge of the corresponding rear side section and having its lower edge curved to conform to the shape of the leg of the wearer and having an opposite diagonally disposed edge aligned with the diagonal edge of the other front section and terminating in a transverse free edge portion which constitutes the lower edge of the concealed fly, lines of stitching securing all of the aforesaid sections together, the aforesaid crotch sections being formed of two separate strips of material of sufficient width to form a pouch, and having a central line of stitching securing these sections together.

5. In a garment of the type described, the combination of a central rear section of uniform

width from end to end and having a concave lower edge, like lateral rear sections each having a slanting bottom edge, a pair of like crotch sections, said crotch sections having convex rear 5 upper edges, curved side edges and terminating in opposite diagonally disposed slanting front edges, the front section having its side edge of similar length to the side edge of the adjacent rear side section and having the bottom edge 10 curved to the shape of the leg of the wearer and having a diagonally disposed front edge aligned with the adjacent diagonal edges of the crotch section, a mating front section having its side edge of the same length as the side edge of the 15 corresponding rear side section and having its lower edge curved to conform to the shape of the leg of the wearer and having an opposite diagonally disposed edge aligned with the diagonal edge of the other front section and terminating in a transverse free edge portion which constitutes the lower edge of the concealed fly, and lines of stitching securing all of the aforesaid 20 sections together.

WILLIAM MURPHEY.
